UNITED STATES PATENT OFFICE.

ALBERT BROADMEYER, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA.

RULING APPARATUS.

1,344,166.

Specification of Letters Patent. Patented June 22, 1920.

Application filed September 22, 1919. Serial No. 325,370.

To all whom it may concern:

Be it known that I, ALBERT BROADMEYER, a citizen of the United States, residing at Harrisburg, in the county of Dauphin and State of Pennsylvania, have invented certain new and useful Improvements in Ruling Apparatus, of which the following is a specification.

The present invention relates more particularly to drying means for ruled paper. It is well understood that it requires some time for the lines to dry after the paper comes from the ruling mechanism, and it is therefore the custom to carry the separate sheets a considerable distance before they are piled, in order to permit the ink to dry and thus avoid smudging of the work.

The primary object of the present invention is to provide means that will hold the paper flat, thus avoiding its tendency to curl by reason of its dampness from the ink, and avoid danger of displacement from air currents, thereby keeping it in proper shape and permitting each sheet to be delivered flat. Moreover it permits the use of artificial currents of warm air without danger of displacing the sheets and causing the conveying elements to intersect the lines, and thus smear the ink.

30 The preferred embodiment of the invention is illustrated in the accompanying drawings, wherein:—

Figures 1^A and 1^B together constitute a sectional view somewhat diagrammatic in its character through a ruling machine, and illustrating the preferred embodiment of the drying mechanism.

Fig. 2 is an end elevation of the same.

Similar reference numerals designate corresponding parts in all the figures of the drawings.

In the embodiment disclosed, a suitable supporting frame 3 is employed, on which is mounted a bed plate or table 4. The upper face of this table is convexed in form. An endless conveyer belt 5 has an upper stretch 6 that moves longitudinally over the table 4, and has a lower return stretch 7. The belt passes around a rear roller 8 of relatively large diameter and around a front

driving drum or roller 9 actuated by any suitable source of power, not shown. A guide roller 10, located in advance of the table 4, serves to hold the portion of the belt in advance of said table in depressed relation so as to insure that the portion of the conveyer moving over the table is smooth and flat thereon. Supporting rollers 11 are interposed between the roller 9 and roller 10, and serve to maintain the belt between the said rollers 9 and 10 in substantially convexed relation. The lower stretch 7 of the belt is guided by suitable rollers 12, and terminates at a relatively small roller 13 located below the driving drum 9. A tension roller 14 is located slightly below and in rear of the drum 9, the belt 5 passing around said roller 14 on the opposite side to the drum 9, as will be clear by reference to Fig. 1^A.

Operating over the upper stretch 6 of the belt 5 are suitable ruling instrumentalities, comprising pens 15 carried by beams 16. It is believed to be unnecessary to go into detail regarding these instrumentalities, as they may be of any well known or desired construction, though preferably of the character disclosed in my co-pending application, Serial No. 325,368, filed September 22, 1919. A suitable gage or gate 17, located over the central of the rollers 11, determines the passage of the sheets to the ruling devices.

In order to insure the proper movement of the paper with the belt 5, endless holding cords or bands 18 have lower stretches that rest upon the outer face of the upper stretch 6 of the belt. These cords or bands pass around a roller 19 located above the drum 9, thence beneath the roller 10 and around a rear roller 20 located above the upper stretch of the belt 6 in advance of the rear roller 8. Suitably elevated guide rollers 21 and 22 support the return upper stretches of the cords or bands, and guides 23 adjustably mounted on a supporting rod 24, determine the positions of the cords or bands 95 transversely of the belt.

Located in the lower portion of the frame beneath the upper belt 5, is a lower endless belt 25 having an upper substantially horizontal stretch 26 and a lower return stretch 100

27. The rear portion of the belt passes around a relatively small roller 28 and a lower roller 29 of larger diameter. The front portion of said belt 25 passes around the front portion of a guide roller 30 of relatively large diameter and around a roller 31 placed within the belt and located above the roller 30. Another guide roller 32, disposed in advance of and below the roller 30, serves 10 as an additional guide for the belt 25.

Interposed between the lower stretch 7 of the upper belt 5 and the upper stretch 26 of the lower belt 25, are endless holding bands or cords 33, each having an upper stretch 34 extending longitudinally along and in coaction with the outer face of the lower stretch of the upper belt 7. They also have lower stretches 35 located longitudinally upon and coacting with the upper stretch 26 of the lower belt 25. The cords or bands at their rear ends pass around the roller 8 and around a guide roller 36 located above and slightly in advance of the roller 8. The rear portions are furthermore passed 20 through guides 39 slidably mounted on a supporting rod 40, the guides 39 determining the positions of the cords transversely of the belt. The front portions of the cords or bands 33 pass around the roller 30, being 25 interposed between said roller and the outer face of the band 25. Their rear portions are furthermore guided by a roller 41 located adjacent to the roller 28, and a guide roller 42, located between the roller 41 and the 30 guide roller 12.

The space thus left below the rear portion of the upper belt 5 and the corresponding portions of the bands or cords 33, is occupied by coacting endless delivery bands 43 carried on pulleys 44. The adjacent coacting faces of said bands 43 are substantially in line with the coacting stretches 26 and 35 of the lower belt and cords or bands.

The operation is substantially as follows. 45 Sheets of paper, successively introduced between the rollers 9 and 19, are caught by the coacting stretches 6 and 18, and when the gage or gate 17 is raised, are passed into the machine and beneath the ruling instruments, which produce the lines thereon. After passing the ruling apparatus, they are released from the cords 18 and are carried by the upper stretch of the belt 6 to the drum 8. Here they are engaged between 50 the belt 5 and the cords 33 and are consequently carried around the drum and are held against the under face of the lower stretch of the upper belt 7 by the upper stretches 34 of the bands or cords 33. They 55 are thus carried back to the front of the machine, and it will be noted that during this portion of their travel, they are securely held, so that they are not only maintained flat and against any curling tendency due to

the damp ink, but cannot be displaced by air currents or any vibration of the parts. Reaching the front end of the machine, the belt 5 is removed therefrom by passing around the roller 13, but the sheets are immediately caught between the belt 25 and 70 the cords 33, and are carried around the roller 30. They are held upon the upper stretch 26 of the belt 25 by the lower stretches 35 of the cords or bands 33, and are thus caused to again travel the full 75 length of the machine, but rearwardly, being delivered between the rollers 28 and 41 to the delivery bands 43 and being passed by said bands to a suitable deposit receptacle or "lay-boy."

It is to be noted that they are thus caused to travel through a lengthy path and are at all times held in flat condition and against curling. Experience has demonstrated that with this structure but few cords are necessary—ordinarily three being sufficient in the lower set thus obviating the danger of the cords striking the ruled lines and smearing the paper. Currents of air, either natural or artificial will also cause no displacement, and the work can consequently be artificially dried without danger of mishap.

From the foregoing, it is thought that the construction, operation and many advantages of the herein described invention will 95 be apparent to those skilled in the art, without further description, and it will be understood that various changes in the size, shape, proportion and minor details of construction, may be resorted to without departing 100 from the spirit or sacrificing any of the advantages of the invention.

Having thus fully described my invention, what I claim as new, and desire to secure by Letters Patent, is:—

105

1. In apparatus of the character described, the combination with an endless work-conveying belt having upper and lower stretches, of ruling mechanism operating over the outer face of the upper stretch of 110 the belt, means for holding the work to said face during its movement past the ruling mechanism, and means separate from the first-mentioned means for maintaining the ruled work against the under face of the 115 lower stretch of the belt.

2. In apparatus of the character described, the combination with an endless work-conveying belt having upper and lower stretches, of ruling mechanism operating over the outer face of the upper stretch of the belt, a set of endless holding devices located above the upper stretch and having lower stretches coacting with the said outer 120 face of the upper stretch of the belt to hold the work to said face during its movement past the ruling mechanism, and another set of endless holding devices coacting with the 125

under face of the lower stretch of the belt to maintain the ruled work against the same.

3. In apparatus of the character described, the combination with work conveying mechanism, including an upper stretch of belting, a lower stretch of belting and an intermediate stretch of belting between the upper and lower stretches, of ruling mechanism coöperating with the uppermost stretch, and a set of endless holding devices having upper stretches coacting with the underside of the intermediate stretch of belting and lower stretches that rest upon the upper face of the lower stretch of belting to hold the ruled sheets thereupon.

4. In apparatus of the character described, the combination with work-conveying mechanism, including upper and lower stretches of belting and an intermediate stretch located between said upper and lower stretches, of a rear guide roller for the belting between the upper and intermediate stretches, a front guide roller for the belting between the intermediate and lower stretches, ruling mechanism coöperating with the outer face of the upper stretch, and a set of endless holding devices passing around both the guide rollers and having upper stretches coacting with the underside of the intermediate stretch of belting, said holding devices having lower stretches coacting with the upper face of the lower stretch of belting, said belting being interposed between the rear guide roller and the holding devices and said holding devices being interposed between the front guide roller and the belting.

5. In apparatus of the character described, the combination with an endless work-conveying belt having upper and lower stretches, of ruling mechanism operating over the outer face of the upper stretch of the belt, a roller around which the belt passes in rear of the ruling mechanism, endless holding devices extending longitudinally along the outer face of the upper stretch of the belt and means for directing said holding devices away from the belt in advance of the roller, a second roller located above and in advance of the first-mentioned roller, and other endless holding devices extending around the upper roller in spaced relation to the belt, thence around the rear portion of the lower roller outside the belt and longitudinally along the under face of the lower stretch of the belt in coaction therewith to maintain the ruled work against said lower stretch of the belt.

6. In apparatus of the character described, the combination with a plurality of endless work-conveying belts located one below the other, of a plurality of endless holding bands or cords operating between the belts, the upper stretches of the bands or cords coacting

with the outer face of the lower stretch of the upper belt and the lower stretches of the band or cord being located upon and coacting with the upper face of the upper stretch of the lower belt.

7. In apparatus of the character described, the combination with a plurality of endless work-conveying belts located one below the other and each having an upper and a lower stretch, of ruling means operating over the upper stretch of the upper belt, and endless holding devices interposed between the belts, the upper stretches of the holding devices extending longitudinally along and coacting with the outer face of the lower stretch of the upper belt to hold the ruled work thereagainst and the lower stretches of the holding devices extending longitudinally along and coacting with the outer face of the upper stretch of the lower belt, to hold the ruled work thereagainst.

8. In apparatus of the character set forth, the combination with a plurality of endless work conveying belts located one below the other and each having an upper and a lower stretch, of ruling means operating over the upper stretch of the upper belt, endless holding devices interposed between the belts, the upper stretches of the holding devices extending longitudinally along and coacting with the outer face of the lower stretch of the upper belt to hold the ruled work thereagainst and the lower stretches of the holding devices extending longitudinally along and coacting with the outer face of the upper stretch of the lower belt to hold the ruled work thereagainst, means for causing the rear portion of the holding devices to pass around and above the rear portion of the upper belt, and means for causing the front portion of the lower belt to extend in advance and above the lower stretches of the holding devices.

9. In apparatus of the character described, the combination with a plurality of endless work conveying belts located one below the other and each having an upper and a lower stretch, of ruling mechanism operating over the upper stretch of the upper belt, endless bands or cords operating over the outer face of the upper stretch of the upper belt, rollers around which said endless cords or bands extend, guides for the cords or bands, a rear roller for the upper belt, a front roller for the upper belt, a tension roller located in rear of the front roller and around which the upper belt passes, a small rear roller for the lower belt, a larger front roller around which the front portion of the lower belt passes, a guide roller located above the larger front roller and around which the lower belt passes, endless bands or cords interposed between the belts, guides for said endless bands or cords, a roller located above

4
the rear roller for the upper belt, said bands or cords passing around the last mentioned roller and around the rear roller for the upper belt and extending longitudinally along and coacting with the outer face of the lower stretch of the upper belt, said cords or bands also extending around the larger front roller of the lower belt and having lower

stretches extending longitudinally along and upon the upper stretch of the lower belt. 10

In testimony whereof, I affix my signature in the presence of two witnesses.

ALBERT BROADMEYER.
